UNITED STATES PATENT OFFICE

HENRY E. WEBER, OF CANTON, OHIO

CONTROLLER FOR DENTAL ENGINES

Application filed May 26, 1927. Serial No. 194,359.

This invention relates to controllers for dental engines; and the object of the improvement is to provide means whereby the controller may be held in position to operate the engine at any desired speed, either forward or reverse, said means being so arranged that it may be rendered inoperative when it is desired to manually hold the controller in the desired position.

10 The above and other objects may be attained by constructing the controller in the manner illustrated in the accompanying drawings, in which

Figure 1 is a side elevation of the improved controller;

Fig. 2, a side elevation of the same, taken substantially at right angles to Fig. 1;

Fig. 3, a top plan view of the controller;

Fig. 4, a bottom plan view with the base plate removed; and

Fig. 5, an enlarged sectional view of one end of the operating lever.

Similar numerals refer to similar parts throughout the drawings.

25 The controller mechanism is located within a cylindric casing 1 mounted upon the base plate 2 and spaced therefrom as by the lugs 3 which may be formed integral with the base plate. The base plate may be provided with 30 the plates 4 for resting upon the floor.

The cable 5 leads from the controller mechanism to the dental engine, and a handle 6 may be provided upon the cover 7 of the casing for moving the controller to any desired 35 location.

The lever 8 is connected at its center to the controller shaft 9 and located between the base plate and the cylindric casing 1, the ends thereof extending outward beyond the cylindric casing and being provided with the enlarged foot engaging portions 10.

40 As shown in Fig. 4, a roller 11 may be mounted upon the lever 8, at one side of its pivotal point for engagement with the fingers 12 which are pivoted to the under side of the cylindric casing as at 13 and normally urged toward each other by the spring 14.

Each of the enlarged ends 10 of the lever is provided with the cylindric portion 15.

45 50 A cylindric bearing block 16 is slidably

mounted in the inner end portion of the bore 17 of said cylindric portion 15, and has journaled therein a roller 18.

This roller is arranged to be normally held in engagement with the peripheral surface of the cylindric casing 1 by means of a plunger 19, slidably mounted in the bore 17 and provided with the hollow outer end portion 20 which receives the coil spring 21, the outer end of which is received in the hollow screw 22 whereby the plunger 19 is normally pressed against the bearing block 16.

55 For the purpose of withholding the pressure of the plunger 19 from the bearing block 16, a stud 23 is carried by the plunger and extended through the longitudinal slot 24 in the upper surface of the cylindric portion 15 and provided with a head 25 preferably knurled as shown so that the same may be easily operated by the foot.

60 This slot 24 is provided with the transverse portion 27 at its outer end, adapted to receive the stud 23 when the same is pulled backward and rocked into said transverse portion of the slot as shown in Figs. 2 and 5.

65 A series of rounded sockets 28 is provided in the peripheral surface of the cylindric casing 1 adjacent to each of the end portions 10 of the operating lever and adapted to be engaged by the rollers 18 when the plunger is 70 in the normal position.

75 Normally the lever is held in the full line position shown in the drawings. When this lever is pushed into the dotted position shown at 15^a in Fig. 3, the dental engine will be 80 operated in forward rotation at the highest speed, and the speed will be decreased proportionately at any position between that shown at 15^a and the normal position of the lever shown in full lines.

85 If the plunger upon the right side end of the lever is in normal position, it will be seen that the roller 18 carried thereby will engage with the adjacent sockets 28 in the cylindric casing of the controller and the lever may thus 90 be held in any desired position.

95 If it is desired to operate the dental engine in reverse, the lever 15 is moved to the dotted line position 15^b shown in Fig. 3. The reverse speed of the dental engine will, of 100

course, be proportionately increased or decreased by locating the lever at intermediate positions between 15^b and that shown at 15 in full lines in Fig. 3.

5 If the plunger in the left side end of the lever 15 is in the normal position, it will be seen that the roller 18 carried thereby will engage with the adjacent sockets or notches 28 in the cylindric controller casing. Thus by 10 moving the lever with the toe to any desired position the dental engine may be operated at the desired speed forward or reverse, the lever remaining in the adjusted position until released.

15 If it is desired to operate the controller by holding the lever in the desired position by the foot of the operator, the studs 23 may be moved into the transverse portions 27 of the slots 24, thus holding the plungers 19 20 withdrawn, as best shown in Fig. 5, whereby the rollers 18 will not be pressed into engagement with the sockets or notches 28 and the lever may be freely moved to any point between the positions 15^a and 15^b shown in Fig. 25 3, and as soon as the foot is removed therefrom, the lever will immediately assume the normal position shown at 15 in said figure, being controlled by the spring pulled fingers 12 shown in Fig. 4.

30 I claim:

1. In a controller for a dental engine including a cylindric casing, an operating lever pivotally mounted concentrically of the casing at one end of the casing, the ends of the 35 lever extending outward beyond the casing, enlarged foot engaging portions extending from each end of the lever adjacent the outer surface of the casing, a plurality of series of diametrically disposed spaced sockets in the 40 outer surface of the casing, and means carried by each foot portion for selective engagement with certain of said diametrically disposed sockets.

45 2. In a controller for a dental engine including a cylindric casing, an operating lever pivotally mounted concentrically of the casing at one end of the casing, the ends of the lever extending outward beyond the casing, enlarged foot engaging portions extending 50 from each end of the lever adjacent the outer surface of the casing, a plurality of series of diametrically disposed spaced sockets in the outer surface of the casing, and spring pressed means carried by each foot portion 55 for selective engagement with certain of said diametrically disposed sockets.

60 3. In a controller for a dental engine including a cylindric casing, an operating lever pivotally mounted concentrically of the casing at one end of the casing, the ends of the lever extending outward beyond the casing, enlarged foot engaging portions extending 65 from each end of the lever adjacent the outer surface of the casing, a plurality of series of diametrically disposed spaced rounded

sockets in the outer surface of the casing, and rollers carried by each foot portion for selective engagement with certain of said diametrically disposed rounded sockets.

4. In a controller for a dental engine including a cylindric casing, an operating lever pivotally mounted concentrically of the casing at one end of the casing, the ends of the lever extending outward beyond the casing, enlarged foot engaging portions extending 70 from each end of the lever adjacent the outer surface of the casing, a plurality of series of diametrically disposed spaced rounded sockets in the outer surface of the casing, and spring pressed rollers carried by each 75 foot portion for selective engagement with certain of said diametrically disposed rounded sockets.

5. In a controller for a dental engine including a cylindric casing, an operating lever pivotally mounted concentrically of the casing at one end of the casing, the ends of the lever extending outward beyond the casing, enlarged foot engaging portions extending 80 from each end of the lever adjacent the outer surface of the casing, a plurality of series of diametrically disposed spaced sockets in the outer surface of the casing, means normally maintaining the lever in a predetermined diametric position relative to the casing, means carried by each foot portion for 85 selective engagement with certain of said diametrically disposed sockets for holding the lever in other diametric positions opposed to the action of said last mentioned means, and means rendering the foot portion means inoperative.

In testimony that I claim the above, I have hereunto subscribed my name.
